BIRDHOUSE

Filed Jan. 16, 1950

FIG. 1.

FIG. 2.

FIG. 3.

INVENTOR
EARL T. WORDEN.

By Howard J. Whelan,
ATTORNEY.

UNITED STATES PATENT OFFICE

163,666

BIRDHOUSE

Earl T. Worden, Baltimore, Md.

Application January 16, 1950, Serial No. 7,289

Term of patent 14 years

(Cl. D31—2)

To all whom it may concern:

Be it known that I, Earl T. Worden, a citizen of the United States, residing at Baltimore city, State of Maryland, have invented a new, original, and ornamental Design for a Bird House, of which the following is a specification, reference being had to the accompanying drawings, forming a part hereof.

Figure 1 is a view in perspective of a bird house, showing my new design;

Figure 2 is a front view of Figure 1; and

Figure 3 is a side view of Figure 1.

I claim:

The ornamental design for a bird house, as shown.

EARL T. WORDEN.
